Patented Jan. 3, 1922.

FIG. II.

FIG. I.

INVENTOR
EDWARD RITTENHOUSE

John C. Bergner
ATTORNEY

UNITED STATES PATENT OFFICE.

EDWARD RITTENHOUSE, OF PHILADELPHIA, PENNSYLVANIA.

THREAD GUIDE FOR SPINNING MACHINES.

1,402,538.

Specification of Letters Patent.

Patented Jan. 3, 1922.

Application filed June 10, 1918. Serial No. 239,106.

To all whom it may concern:

Be it known that I, EDWARD RITTENHOUSE, of 2561 N. Front St., Philadelphia, in the county of Philadelphia and State of Pennsylvania, have invented certain new and useful Improvements in Thread Guides for Spinning Machines, whereof the following is a specification, reference being had to the accompanying drawings.

10 The invention relates to thread guides for spinning machines, and is more especially useful in machines of this general class adapted for spinning artificial silk.

In the course of the manufacture of such silk, a plurality of strands are formed by a spinneret, and after passing through a suitable coagulating solution are subsequently twisted into a single thread. Contemporaneous with this twisting action, the thread 15 is collected in the form of an annular "cake," in a receiving box rotating at a very high speed. The twisting of the grouped strands, and the building of the cake in the receiving box are due to the resultant of the rate at 20 which the strands are fed and the centrifugal force occasioned by the high rotative speed already referred to. In order to obtain a perfect thread, it is absolutely essential that the bunched strands of cellulose be at 25 all times accurately directed to a central point within the receiving box.

The primary object of my invention is to insure the relation just described. To this end it includes a thread guide having a comparatively long counter weighted shank or stem, freely suspended from a suitable support, so as to readily yield to the constant angular pull of the thread occasioned by centrifugal force as above noted and, as a 35 result be, automatically maintain an accurate central position with respect to the receiving box.

Other objects and attendant advantages of my invention will become readily apparent from the detailed description which follows.

In the drawings, Fig. I is a cross-sectional view through the twisting mechanism of an artificial silk spinning machine conveniently 50 illustrating my invention.

Fig. II, is a similar view of a slightly modified form of my invention.

Referring to Fig. I, of the drawings, the spindle of the machine designated by the 55 numeral 1, is surmounted by an integral collar 2, which serves as a seat for a receiving

box 3, and displacement of the latter is prevented by a central stud 5, projecting from said collar. The spindle is adapted to be driven at a high rate of speed and since this 60 may be effected by any approved means, illustration thereof has been deemed unnecessary.

The thread guide embodying the novel features of my invention in their simplest form, is represented in Fig. I. As therein shown, it consists of a tubular shank 6, terminating at the top in a hemispherical funnel 7, which seats in a correspondingly shaped countersunk apertured seat 8, in a 70 supporting rail partly represented at 9. By this construction, the guide is freely suspended from its support in such a manner as to be sensitive to a delicate pull induced by gyration of the thread as will be more 75 clearly hereinafter described. The lower or free end of the guide terminates in a thickened weighted portion 10, preferably spherical in form. This serves in effect as a stabilizer tending to hold the guide in a central 80 position and at the same time prevent excessive deflection of the guide from the vertical position shown.

In the course of the operation of the machine, the guide supporting rail 9, is slowly 85 reciprocated vertically so as to cause the building of the cake represented at "C" in the box. This building action is effected through the velocity induced upon the thread by virtue of the high speed rotation 90 of the receiving box in connection with the attendant linear movement of the strands from the end of the guide. The pull thus created by the rotation of the box is equal in all directions so that, owing to the free suspension of the guide, its lower end will at 95 all times assume a central position with respect to the receiving box 3, notwithstanding any inaccuracies of alignment of the seat 8, with relation to the spindle center. 100

Under these conditions, a uniform thread is assured owing to the constant relation thus established.

In Fig. II, I have illustrated a slightly modified form in which the general arrangements 105 and resultant functions are the same as those already described. In this instance, the weighted portion is in the form of a collar 30, which is held in place upon the shank of the guide by washers 31—31, of rubber or 110 like material.

This method of suspension differs from

the former showing in that a resilient washer 32, is interposed between the funnel 7, and the countersunk seat 8. By this construction, the guide is primarily centered by 5 the co-operation of the washer 32, with the seat while the weighted end of the guide, in finding its own center as already described, is independently permitted to shift accordingly by virtue of the inherent yielding nature of the resilient washer.

This second form of my invention will thus be operative notwithstanding any sticking which may occur between the washer 32, and the seat 8, which would ordinarily tend to defeat the desired object of 15 the invention.

It is to be understood that I do not wish to limit myself to the precise details of arrangement and construction herein shown 20 since various modifications may be made therein without departing from the spirit of my invention.

Having thus described my invention, I claim:

25 1. In a device of the character described, the combination with a rotating spinning box for receiving the finished thread, of a cooperative thread guide adapted to be reciprocated axially within the spinning box to 30 effect distribution of the thread as it accumulates therein, said guide having capacity for automatic self centralization within the receiving box under constant angular pull induced by gyration of the thread during its 35 spinning.

2. In a device of the character described, the combination with a rotating spinning box for receiving the finished thread, of a cooperative guide having capacity for 40 automatic self centralization within the spinning box under constant angular pull induced by gyration of the thread during its spinning.

3. In a device of the character described, the combination with a rotating spinning 45 box for receiving the finished thread, of a cooperative thread guide of tubular form freely suspended at its upper extremity so that its lower end may be automatically maintained accurately centralized within 50 the spinning box under constant angular pull induced by gyration of the thread during its spinning.

4. In a device of the character described, the combination with a rotating spinning 55 box for receiving the finished thread, of a cooperative tubular guide freely suspended at its upper extremity and weighted at its lower end so that the latter may, under the stabilizing influence of the weighting, yield 60 to constant angular pull induced by gyration of the thread during its spinning and thereby be held automatically centered within the spinning box.

5. In a device of the class described, the 65 combination with a spindle of a thread guide consisting of a tubular shank having a headed portion, and a weighted free end; means for loosely supporting said guide including a suspension rail having an apertured seating recess; a resilient washer engaging the shank of the guide directly beneath the headed portion and adapted to automatically center itself in the recess of said supporting rail, the resiliency of said washer 70 permitting an independent play of the weighted free end of the guide with respect to said spindle substantially as shown and for the purpose set forth.

In testimony whereof, I have signed my 80 name, at Philadelphia, Pennsylvania, this thirty-first day of May, 1918.

EDWARD RITTENHOUSE.
